UNITED STATES PATENT OFFICE.

DAVID CHARLES WILLIAMSON, OF NEW YORK, N. Y.

TABULATOR FOR TYPE-WRITING, TYPE-SETTING, OR ANALOGOUS MACHINES.

SPECIFICATION forming part of Letters Patent No. 559,921, dated May 12, 1896.

Application filed December 29, 1894. Serial No. 533,270. (No model.)

To all whom it may concern:

Be it known that I, DAVID CHARLES WILLIAMSON, a citizen of the United States, residing in New York, in the county of New York 5 and State of New York, have invented certain new and useful Improvements in Tabulators for Type-Writing, Type-Setting, or Analogous Machines, of which the following is a specification.

10 This invention relates to indicators, guides, or scales for assisting the operator in performing tabular work on such machines as type-writers, type-setters, printing-machines, and the like, and aims to provide an improved 15 tabulator for this purpose.

The invention will be described as applied to a type-writing machine, a use for which it is especially adapted, and for the purposes of illustration it will be shown as used with that 20 type of machine of such class known as the "Remington" type-writer. In type-writers particularly it is customary to employ a movable platen or paper-carriage bearing the paper on which the impression from the type is 25 taken and movable longitudinally throughout regular predetermined spaces, called "letter-spaces," to provide for the succeeding letters or other characters going to make up a printed line, and movable laterally or relatively to provide for the spaces between the 30 lines known as "line-spaces." This carriage moves relatively to a stationary base. On one of the parts is a point or index and on the other a scale or index, these devices being 35 movable, the one relatively to the other, to indicate the point at which the impression will be made. The scale is usually the fixed member and the pointer the movable member, the former corresponding with the length of line 40 printed by the machine and the latter indicating on the former the number of the space at which each succeeding impression will be made. In tabulation on such machines it is necessary to note the number of the space at 45 which the decimal point of the first line of figures or characters is placed or some other point which shall be common to all the succeeding lines, and thereafter, in printing subsequent lines, to compute from this point the 50 number of spaces to be required by each succeeding line and then adjust the carriage accordingly. This requires great care, consumes

much time, and involves considerable risk of error. To expedite this operation, tabulators have heretofore been applied beyond the end 55 of the carriage and have consisted of plates or levers constituting guides and stops, by operating which the carriage could be stopped at a certain point.

My present invention aims to provide a 60 simple attachment for machines of the class specified which shall be convenient and effective for assistance in the operation of tabulating and shall not interfere with the ordinary use, size, or convenience of the machine. 65

To this end in carrying out my invention I provide the improvements which will be hereinafter fully set forth, and specified in the claims.

In the accompanying drawings, Figure 1 is 70 a fragmentary front elevation of the frame and carriage of a type-writer provided with the preferred form of my improved tabulator. Fig. 2 is a perspective view of the tabulator therein shown on a larger scale. Fig. 3 is a 75 side elevation thereof, the scale-bar carrying it being in section.

Referring to the drawings, let A indicate the frame of the type-writer; B, the carriage thereof; C, the printing-roll; D, the paper carried thereby; E, the scale on the frame A; F, the carriage-track; G, the antifriction-wheel of the carriage riding on this track, and H the pointer or index on the carriage and co-operating with the scale to indicate the space or 85 point at which the succeeding type-impression will be made on the paper. As thus far described, the parts are or may be of any known, usual, or suitable construction, it being only essential that the machine shall have 90 a pointer or indicator and a scale or index, the one movable relatively to the other and jointly serving to indicate the point or points at which succeeding impressions shall be made. 95

My invention provides an improved tabulating device for facilitating the operation of printing a plurality of lines of figures or characters in a vertical column, and this device comprises an auxiliary scale or index and a 100 pointer, the one movable relatively to the other in correspondence with the relative movement between the impression-giving and the impression-taking parts of the machine,

and the one having graduations or suitable marks indicating an initial or prominent point or space to be taken as a guiding point or space in effecting the tabulation. In its preferred form the pointer is the movable member and the scale the normally stationary member, the former carried by the carriage and permanently located relatively thereto and the latter carried by the frame and adjustable thereon. In this form the auxiliary scale is best constructed as a piece I, and the pointer or index utilized may be that ordinarily employed, in the construction shown the pointer H. The piece I according to my invention has distinctive marks or graduations J, those shown being identical in their ordinary construction with the graduations K of the scale E, but the graduations J are peculiarly arranged or distinguished to represent a certain part or parts of a tabular column. Those shown, which are especially designed for use with the metric system, for example, in the tabulation of sums in dollars and cents, have a distinctive point *a*, represented by a blank or double space standing over the decimal point, at left of which are two marks or points *b*, standing, respectively, for tenths and hundredths of a unit, or dimes and cents, and at right of which are three marks *c*, standing, respectively, for units, tens, and hundreds. Following this is a blank or double space or other distinctive portion *d*, representing the division between hundreds and thousands, beyond which are three more marks or divisions *e*, representing thousands and tens and hundreds of thousands, followed by another distinctive divisional portion *f*, indicating the space between hundreds of thousands and millions, and two or more marks *g*, indicating millions and tens of millions.

In use the auxiliary scale and pointer are relatively adjusted to bring the space *a* coinciding with the one impression position of the impression-taking member of the machine at which it is desired that the decimal point of a column of figures shall be situated, in such manner that when the pointer is opposite this point or space the impression will be correspondingly situated on the paper, and then from this adjustment the starting-point for each line of figures is computed by simply reading on the auxiliary scale the figures of the line to be printed and adjusting the pointer from the decimal point to the commencement of such line of figures by shifting the impression-taking member accordingly. If, for example, \$6,543.21 is to be written, and the pointer stands at the decimal space *a*, the operator will shift the carriage to the right until the pointer coincides with the graduation standing for thousands, when he will print "6," and the carriage will then feed itself to the adjacent dividing-space *d*, where he may print a comma or simply leave a blank by striking the space-key, thus bringing the pointer to the hundreds-mark, where he will

print a "5," bringing the machine to the tens-mark, where he will print a "4," and then to the units, where he will print a "3," thus carrying the pointer to the decimal mark, where he will print a decimal point, thereby feeding the pointer to the dimes-mark, where he will print a "2," from whence it moves to the cents-mark, where he will print a "1." Now to bring a succeeding line properly beneath the line thus printed, the operator will move the carriage until the pointer coincides with the mark corresponding with the first figure in the new line without paying any particular attention to the location of the previous line. If the first figure is in the tens column, he will simply shift the pointer until it reaches the tens-mark and strike in his figures, which we will say are \$10. For the next line, which we will say is \$100,000, he will shift the carriage until the pointer reaches the hundreds of thousands mark and print in this line without the necessity of observing the others. It follows, from the fact that the first line of the table has corresponded with the graduations of the tabulator, that each subsequent line, so long as the tabulator is undisturbed, is properly disposed relatively to those preceding it. Hence the operator is not put to the necessity of memorizing any point of the column nor of computing the starting-point for any line of figures.

To enable the location of the column of figures at any point on the impression-taking member, the auxiliary scale and the pointer must be relatively adjustable, so that the one can be brought into coincidence with the other at any position of the impression-taking member, and to facilitate the location of the column at the desired point relatively to the ordinary scale of the machine the adjustable portion of the tabulator should be disposed relatively to the ordinary scale to indicate with what part of the latter its graduations are corresponding. To accomplish both these purposes, I prefer to mount the adjustable part of my improved tabulator on or in proximity to the ordinary scale of the machine and construct this part so that both its graduations and the ordinary graduations shall be visible to the operator. This part is usually the scale-piece I, which, as shown in Figs. 1, 2, and 3, consists of a thin plate of elastic metal having a body *h*, lying flat on and detachable from the scale-plate E, having an outwardly-projecting handle portion *i*, elastic clips *j*, frictionally embracing the inner side of the scale-bar E, inwardly-projecting ears *k* opposite said clips and embracing the edge of the scale-bar E to prevent the displacement of the piece, a guide or indicator L for coinciding with the graduations K to indicate when the tabulator-scale is in proper position relatively to the ordinary scale, a fastening lock or catch M, snapping into the indentations of the graduations K to assist in checking the auxiliary scale in coincidence with the graduations of the ordinary scale to fasten it

- thereto and to prevent its accidental displacement, and visual parts *n*, through which may be seen the numbers of the ordinary scale. These points are preferably all formed from 5 a single integral sheet of metal bent to the proper form and having at front a cut-out place *N*, through which the minor graduations of the ordinary scale may be seen. To advance the ordinary scale-bar *E* from the frame 10 *A* sufficiently to make room for the clips *j*, I insert a wire or rod *O* between the bar *E* and the frame *A*, passing the looped ends of this rod around the usual fastening-screws *P*, as shown in Figs. 1 and 3.
- 15 It will be seen that my invention provides an improved tabulator for type-writing and like machines, which can be variously and conveniently availed of, and it will be understood that the invention is not limited to 20 the particular features of construction and arrangement set forth and shown, as it may be employed according to such modifications thereof as circumstances or the judgment of those skilled in the art may dictate without 25 departing from the spirit of the invention.
- In machines of the character shown, wherein the scale *E* is fixed to the frame and the pointer *H* moves with the carriage, the scale is known as a "reverse" scale or graduation, 30 because its readings are taken in the opposite direction to those of the resulting printing. To avoid this, it is customary to transpose the ordinary scale and pointer, putting the former on the carriage and the latter on 35 the frame, so that the pointer is stationary and the scale moves past it. This gives what is known as "regular indication," the scale and the printed matter corresponding in position and both reading from the same point.
- 40 This transposition does not effect any material change in the function of these parts and does not present any obstacles to the use of my invention with them.
- To facilitate the use of the auxiliary tabulating-scale with an ordinary scale, which is 45 either fixed relatively to a movable pointer or movable relatively to a fixed pointer, my invention comprises as one of its features in its preferred form the construction of the 50 tabulating-scale as a reversible part, which may be employed with the use of either end as the initial or prominent point of the scale. This is best accomplished in the manner shown, wherein in Figs. 1 and 2 the scale *I* 55 has at each end graduations which are exact duplicates of those at the other end. For example, the prominent point or space *a* and the prominent point or space *f* correspond in position and in relation to the remainder of 60 the graduations with each other, and at the outer side of each are two graduations, those *b* being at the left of the point *a*, and those *g* at the right of the point *f*. In the use shown in Fig. 1 the graduations *b* would correspond 65 to tens and hundreds of a unit and the graduations *g* to millions and tens of millions; but were the ordinary scale movable and the

pointer stationary, if the auxiliary scale maintained the position shown relatively to the pointer, the graduations *g* would stand 70 for tens and hundreds of a unit and the graduations *b* for millions and tens of millions. When thus constructed, the scale may be slipped onto the ordinary scale of a machine having either reverse or regular graduations, 75 and can be used with equal facility with either, because of the duplication of graduations at its ends.

It will be understood that any number of auxiliary scales may be employed, it being 80 most convenient to use one for each column of figures to be printed when several columns are to be printed side by side; also that the length and the character or relation of the graduations may be varied to suit convenience 85 or the circumstances of use.

What I claim is—

1. In type-writing and analogous machines, a fixed frame, a movable carriage, an ordinary scale fixed to one of said parts, and a 90 pointer carried by the other of said parts and indicating on said scale the impression-taking position, in combination with an auxiliary sliding scale-piece having permanent graduations mounted on, sliding relatively to, and 95 of less length than, said ordinary scale, having graduations adjacent to the graduations of the ordinary scale and exposing the graduations of the latter at a point opposite its own graduations, whereby said pointer indicates 100 the movement of the carriage relatively to both said ordinary and said auxiliary scales and means connecting said ordinary and auxiliary scales, substantially as and for the purpose set forth. 105

2. In type-writing and analogous machines, the combination with the frame, fixed scale having graduations mounted thereon and movable carriage, of an auxiliary scale-piece having permanent graduations mounted on, 110 adjustable on, and of less length than, said fixed scale, and having a visual portion opposite its graduations where the graduations of the fixed scale can be seen, means movably connecting said ordinary and auxiliary scales, 115 and a pointer carried by and moving with said carriage opposite said fixed and auxiliary scales, and indicating on both the movements of the carriage relatively thereto.

3. In type-writing and analogous machines, 120 the combination with the frame, fixed scale thereon and movable carriage, of an auxiliary sliding scale-piece having permanent graduations mounted on, sliding relatively to, and from end to end of and of less length than, 125 said fixed scale, and having a visual portion opposite its graduations where the graduations of the fixed scale can be seen, and a pointer carried by said carriage opposite said fixed and auxiliary scales and indicating on 130 both the movements of the carriage relatively thereto.

4. An attachment for type-writing and analogous machines having an ordinary scale

- 4
- and a pointer, a movable carriage and a frame, said attachment consisting of an auxiliary scale-piece having permanent graduations corresponding with those of said scale, said 5 piece of less length than and adjustable relatively to said ordinary scale, having fastening provisions adjustably engaging said ordinary scale and fastening it thereto, having a portion overlying in use the ordinary scale, 10 and having a visual portion through which the graduations of said ordinary scale can be seen, substantially as and for the purpose set forth.
5. An attachment for application to the 15 ordinary scale of type-writing and analogous machines, consisting of an auxiliary scale-piece having a permanent scale consisting of graduations disposed in use out of line with the graduations of an ordinary scale, having 20 a visual portion through which the graduations of an ordinary scale can be seen, and having fasteners for movably attaching said piece over the ordinary scale of a machine, substantially as and for the purpose set forth.
- 25 6. An attachment for type-writing and analogous machines consisting of a scale-piece I having graduations J, clips j, and indicator L, substantially as and for the purpose set forth.
- 30 7. An attachment for type-writing and analogous machines consisting of a scale-piece I having graduations J, indicator L, clips j, and catch M, substantially as and for the purpose set forth.
- 35 8. An attachment for a type-writing or

analogous machine, consisting of an auxiliary scale-piece having graduations, and having means movably connecting it to the scale of a machine, and having a fastening M fixing it in position on such scale.

9. An attachment for the ordinary scales of type-writing and analogous machines, consisting of an auxiliary scale-piece having a body applicable to an ordinary scale, having 45 graduations adjacent to those of an ordinary scale when the attachment is applied to the latter, having fasteners movably connecting it to an ordinary scale, and having a projecting handle of greater projection than the thickness of said body by grasping which it 50 can be slid on an ordinary scale.

10. An attachment for the ordinary scale of type-writing and analogous machines, consisting of an auxiliary scale-piece having a body fitting on the graduated face of such 55 scale, permanent graduations on said body adjacent to but out of line with those of the ordinary scale when the auxiliary scale is applied thereto, fasteners holding the auxiliary scale to an ordinary scale, and a cut-out part 60 N opposite the graduations of an ordinary scale when the auxiliary piece is applied thereto.

In witness whereof I have hereunto signed my name in the presence of two subscribing 65 witnesses.
